UNITED STATES PATENT OFFICE.

ANNA R. W. BASSETT, OF NORWOOD, PENNSYLVANIA.

DESIGN FOR A FLAG, BANNER, PENNANT, EMBLEM, OR ARTICLE OF SIMILAR NATURE.

55,235.

Specification for Design.

Patented May 25, 1920.

Application filed March 7, 1919. Serial No. 282,459. Term of patent 14 years.

To all whom it may concern:

Be it known that I, ANNA R. W. BASSETT, a citizen of the United States, residing at Norwood, in the county of Delaware and State of Pennsylvania, have invented a new, original, and ornamental Design for Flags, Banners, Pennants, Emblems, or Articles of Similar Nature, reference being had to the accompanying drawing, forming part thereof.

The figure of the drawing is a plan view of a flag, showing my new design.

I claim:

The ornamental design for a flag, banner, pennant, emblem, or article of similar nature, as shown.

In testimony whereof, I have signed my name to this specification in the presence of two subscribing witnesses.

ANNA R. W. BASSETT.
